UNITED STATES PATENT OFFICE.

ANTOINE B. DU PONT, OF DETROIT, MICHIGAN, ASSIGNOR TO THE LORAIN STEEL COMPANY, OF PENNSYLVANIA.

CAR-TRUCK.

SPECIFICATION forming part of Letters Patent No. 661,962, dated November 20, 1900.

Application filed August 29, 1899. Serial No. 728,925. (No model.)

To all whom it may concern:

Be it known that I, ANTOINE B. DU PONT, of Detroit, in the county of Wayne and State of Michigan, have invented a new and useful 5 Improvement in Car-Trucks, of which the following is a full, clear, and exact description, reference being had to the accompanying drawings, which form a part of this specification.

10 My invention has relation to certain new and useful improvements in car-trucks, and more particularly to the frames thereof, being designed to provide a simple, strong, and durable frame construction. I attain this object 15 by the novel means which I will proceed to describe and which are particularly pointed out in the appended claims, reference being had to the accompanying drawings, in which—

Figure 1 is a plan view of a truck embodying my invention. Fig. 2 is a side view of the same, and Fig. 3 an end view.

The truck which I have illustrated in the drawings is of that class described and claimed in prior patents granted to me, in 25 which the side bars of the truck are supported from and below the axle-boxes, and generally known to the trade as the "Du Pont" truck. These side frames are composed of two parallel edgewise-disposed side plates A A, of 30 rolled steel, spaced from each other by distance-blocks and securely bolted or riveted together, the bars at the two sides being connected heretofore by separate end bars. In the improved frame construction shown in 35 the drawings I dispense with the separate end bars and make the side bars of sufficient length to bend across and form the ends of the frame, the two plates being brought closely together and securely riveted, as shown. I 40 prefer also to so arrange the two plates that the joints between their ends will come, respectively, at opposite ends of the truck. In this manner I provide a continuous rigid frame composed, in so far as its side and end 45 members are concerned, of but two pieces, so arranged as to have a large moment of inertia and capable of holding the wheels to alignment.

B designates the truck-wheels; B', the axles; 50 C, the axle-box springs; D, the bolster; D', the

elliptic bolster-springs; D², the swing-links for the bolster; E, the spring-plank, and E' the bolster-guides. These parts are all of the usual or well-known character and arrangement and need not be specifically described. 55

F F' designate the two brake-beams, which are placed between the wheels and are mounted in suitable guides f on the side frames.

G designates the brake-heads secured to 60 said beams, and G' the brake-shoes.

H designates the transverse members of the frame, composed each of two edgewise-disposed bars or plates bolted or riveted at their ends to lugs c of the bolster-guides and connected by rivets h, which pass through them 65 and through interposed spacing-blocks h'.

Secured to the central portion of each brake-beam is a distance-loop I, which extends toward the adjacent axle and in which is pivoted a brake-lever J or J', the lever J being 70 the operating-lever and the lever J' the dead-lever. The pivot-points of these levers are a short distance above their lower ends and the said ends are pivoted to a connecting-link K. Secured to the transverse member of the frame 75 nearest the lever J is a slotted horizontal arm K', through which the upper portion of the lever extends and which is provided with two rows of alternately-arranged perforations k to receive a pin k', which passes therethrough 80 and through the lever.

It will be readily seen that when the lever J is operated to set the brakes the effect is a straight pull through the distance-loop I on the brake-beam F and a similar pull on the 85 beam F through the link K, lever J', and the other distance-loop I. This action overcomes the tendency to twist the brake-beams and cause unequal wear of the brake-shoes, as is usually the case where the shoes are hung inside the wheels.

By means of the plurality of perforations k, arranged alternately of each other in the two rows, the wear of the brake-shoes may be very readily and accurately taken up. 95

I do not wish to limit myself to the particular construction and arrangement which I have shown and described, as the same may be varied in detail without departing from the spirit and scope of my invention. 100

Having thus described my invention, what I claim, and desire to protect by Letters Patent, is—

In a car-truck, a continuous side and end frame supported from and below the journal-boxes, and consisting of a pair of edgewise-disposed plates arranged side by side and separated from each other at the sides of the truck and brought together and rigidly secured to each other at the end portions, distance-pieces secured between the side por-

tions of said plates and supporting the car-springs and journal-box straps, and upwardly-extending bolster-guides also secured between and spacing the side portions of said plates, substantially as specified.

In testimony whereof I have affixed my signature in presence of two witnesses.

ANTOINE B. DU PONT.
